UNITED STATES PATENT OFFICE.

ADOLPHUS DAVIS, OF MONTREAL, QUEBEC, CANADA.

SLEEPING-CAR BERTH.

SPECIFICATION forming part of Letters Patent No. 279,137, dated June 12, 1883.

Application filed November 1, 1882. (No model.)

To all whom it may concern:

Be it known that I, ADOLPHUS DAVIS, of the city of Montreal, in the district of Montreal and Province of Quebec, in the Dominion 5 of Canada, railway manager, have invented certain new and useful Improvements in Berths for Sleeping-Cars; and I do hereby declare that the following is a full, clear, and exact description of the same.

10 This invention has reference to an improved construction and arrangement of the berth-frames, mattresses, and their fittings and attachments, which will be specially adapted for use in combination with the combined sleeping and drawing-room car patented by Gustave 15 Leve on the 5th September, 1876, reissued May 3, 1881, the fittings for which also were patented by me on the 26th April, 1881. The present invention will also be applicable for 20 use with the steamboat-berth also patented by Leve, and for positions where similar berth-fittings would be required.

25 My present invention consists, broadly speaking, in the combination, with a swinging cupboard, of a mattress made up of flat strips of metal constructed in two divisions and hinged in the center, so that the same may be folded inside said cupboard.

30 Certain details of construction and arrangement are also included in my invention; but for full comprehension of the same reference must be had to the accompanying drawings, in which letters similar to those used in the following description indicate like parts, and 35 where—

Figure 1 is a sectional elevation, representing a section of a car arranged as a sleeper embodying my invention. Fig. 2 is an inside view of one of the swinging cupboards, one half of 40 which shows stuffed mattresses held in place by stanchion, and the other half showing metal mattresses folded inside cupboard. Fig. 3 is a view of stanchion, and Fig. 4 a view showing attachment of same to cupboard.

45 A A represent the folding cupboards, which are hinged to the side walls of the car and also supported on brackets B B. On the outsides or backs of these cupboards are fixed combined hooks and berth-supports C C, all these parts 50 being described and claimed in the patents above mentioned.

When the berths are to be made up for the night the cupboards A A are swung out and secured in the position shown in Fig. 1 in the usual manner. The stuffed mattresses D D and 55 the metal mattresses E E' are then inside the cupboards, as shown to the left in Fig. 1 and in Fig. 2—viz., the latter are folded up and securely held against the cupboards by buttons e e or other suitable means, and the stuffed mattresses are hung oversame, one above the other, on pins d d, projecting from the inside of the cupboards A, and the whole is kept firmly in place within the cupboards by the stanchions F F, the lower ends of which are fitted into 60 steps or holders a a, bolted to the lower part of the cupboards and held at their upper ends by clips a a', fastened to the upper part of the cupboards. The first thing to be done is to release the stanchions F F from their holdfasts, and 65 after the metal beds E E' are unfolded and put in place, as will be hereinafter more fully explained, place same in position, as shown in Fig. 1, to form the side rails of the upper and lower berths, each of said stanchions being 70 provided with an eye, f, at one end and a socket, f' at the other, said eyes f being fitted over the pins on the berth-supports C C, and the sockets f', engaged with suitable male supports, f'', arranged at the sides of the berth-frames, as seen 75 in Figs. 2 and 4. The stuffed mattresses D D are then removed from the hooks or pins d d and laid on one side.

The metal mattresses E E' are made up of a suitable number of flat strips of metal, g g, 80 running longitudinally with the bed, which are secured together by cross-strips g' g', and these mattresses are made in two divisions, hinged together at the center, as at g' g''. One end of the mattress for the upper berth, or that marked 85 E, is pivoted or hinged to the inside of one of the cupboards A, as shown at g' in Fig. 1, and its other end has suitable eyes, which fit over the pins of the berth-supports C. The mattress marked E' is constructed in all respects 90 similar to that lettered E, save that instead of having its pivotal connection rigid with the cupboard A it has loops or slots e formed at one end of each outside slat, through which the pivot-pins e' pass in such manner that as the 95 mattress E' is folded it may slide downward on said pivot-pins until the ends of the slats touch 100

the bottom board of the cupboard, in this manner allowing the mattress E' to be easily and conveniently folded against the cupboard A below the ends of the mattress E, arranged 5 above it without overlapping same. The dotted lines in Fig. 1 indicate clearly the passage taken by these folding metal mattresses and the relation of the divisions of same to each other, and the other figures indicate their 10 relation to the cupboards A A.

To complete the formation of the bed after the metal mattresses E E' are unfolded and their loose ends hooked onto the supports CC, and after the stanchions F F are put in place 15 to serve as side rails, as described, the stuffed mattresses D D are laid on with the bed-clothes in the usual manner.

If desired, wood may be substituted for metal in the bed, and the means for attaching same 20 to the cupboards may be varied in detail. And, furthermore, only one bed may be used inside the cupboard; and the loose end of the bed may be supported against a stationary wall or other support instead of to another cupboard, if desired, without departing from my 25 invention.

What I claim, and desire to secure by Letters Patent, is as follows:

1. The combination, with a swinging-berth

cupboard, of a mattress or bed made up of slats, 30 hinged in the center, so as to form two divisions, said mattress being also hinged at one end to said cupboard and adapted to be folded inside same, substantially as and for the purpose set forth.

2. The combination, with the swinging cupboards A A, of the beds or mattresses E E', pivoted to one cupboard and hooked onto another, and stanchions F F, arranged so as to form side rails for same, substantially as set 40 forth.

3. The combination, with the cupboard A and pivot g' , of the metal bed or mattress E', having slots or loops e at the ends of its outer slats, substantially as and for the purpose set 45 forth.

4. The combination, with the cupboards A, provided with steps or holders a a and clips a', of the stanchions F F, arranged as described, for the purpose set forth.

5. The combination, with the cupboards A A, provided with hook-supports G G and male supports f', of the stanchions F, having eyes f and sockets f'', substantially as described.

A. DAVIS.
